INITIALED PULL FOR SEPARABLE FASTENERS

Filed March 19, 1938

UNITED STATES PATENT OFFICE

2,181,281

INITIALED PULL FOR SEPARABLE
FASTENERS

Louis H. Morin, Bronx, N. Y., assignor to White-
hall Patents Corporation, Bronx, N. Y., a cor-
poration of New York

Application March 19, 1938, Serial No. 196,844

6 Claims. (Cl. 40—140)

This invention relates to separable fastener devices employing stringers with a slider movable along the stringers to couple and uncouple the links thereof, and especially to the finger pieces or pulls employed in conjunction with the sliders of devices of this kind. More particularly, the invention relates to the provision of a finger piece or pull having means to receive and support letters, characters, symbols, or other marks of identifications arranged on independent characterizing elements, the latter having means engaging the supporting means of the pull to retain the elements against displacement from the pull, while at the same time facilitating quick and easy assemblage of the characterizing elements with the pull.

The novel features of the invention will be best understood from the following description and annexed drawing in which certain embodiments of the invention are disclosed and in which the separate parts of the invention are designated by suitable reference characters in each of the views, and in which:

Fig. 1 is an enlarged view showing a portion 25 of two stringers with a slider thereon and showing one form of finger piece.

Fig. 2 is a section on the line 2—2 of Fig. 1.

Fig. 3 is a partial section on the line 3—3 of Fig. 1.

Fig. 4 is a view similar to Fig. 1, but showing only the finger piece and illustrating a modification.

Fig. 5 is a section on the line 5—5 of Fig. 4.

Figs. 6 and 7 are cross sectional views illustrating the spaces in forming or shaping the pull; especially as shown in Figs. 1 and 4.

Fig. 8 is a view similar to Fig. 4 showing another modification.

Fig. 9 is a section on the line 9—9 of Fig. 8.

Fig. 10 is a section on the line 10—10 of Fig. 8.

Fig. 11 is a view similar to Figs. 4 and 8 showing another form of construction; and,

Fig. 12 is a section on the line 12—12 of Fig. 11.

In the production of separable fasteners of the character under consideration, it is common to employ finger pieces or pulls in conjunction with the sliders of such devices to facilitate movement of the slider longitudinally of the fastener stringers. These pulls or finger pieces are commonly made in various types and kinds adapting them to the different uses to which the fastener devices may be applied. In some instances and by way of an example, in applying a fastener to a pocketbook, piece of luggage or the like, or even in applying the same to wearing ap-

parel, it is desirable to attach characterized elements to the finger piece to give a specific design thereto, or as a means of identification. For example, the initials of a purchaser may be readily attached to the pull. In fasteners of the 5 class described, these devices are made in various metal forms, and the present invention relates in this respect primarily to finger pieces which are die cast; and in other instances, the devices are made from thermoplastic and similar materials, in which cases, the finger pieces may be die cast from such thermoplastic materials as cellulose acetate.

For the purpose of illustrating the general type of devices to which the invention relates, in Fig. 15 1 are illustrated at 13, 13a, portions of two fastener stringers with the coupling links 14, 14a on one edge thereof, and at 15 is shown a slider movable longitudinally of the stringers to couple and uncouple said links as in other devices of 20 this kind. In this connection, it will be apparent that the slider may be of any desired type and kind, and will have a suitable means such as 16 for pivotally or otherwise coupling a finger piece or pull 17 with the slider.

In the construction shown in Figs. 1 to 3 inclusive, the finger piece 17 is in the form of a unitary and preferably die cast body having a pivoted end portion 18. One side surface 19 of the pull is provided with an elongated recess 20 30 which is bounded on opposite sides with inturned flanges 21; the inner end of the recess terminating in a shoulder 22 whereas the outer end of the recess opens through the end 23 of the finger piece. The upwardly projecting catch or 35 lug 24 is arranged upon the surface 19 within the recess 20, adjacent the end 23 to provide means for retaining two characterized elements 25, 25a, against displacement from the recessed portion of the finger piece.

The elements 25, 25a may simply be in the form of arc-shaped strips of sheet metal having suitable characterizations embossed on the outer surface thereof, such for example the letter L, as seen at 26 and the letter M, as 45 seen at 26a in Fig. 1 of the drawing. These strips may or may not have end walls as desired; the end walls being omitted in the structure shown in Fig. 1, but being illustrated in other figures. With the construction shown in Figs. 1 to 3 inclusive, the elements 25, 25a are simply snapped into engagement with the flanges 21, the retaining clip or projection 24, in conjunction with the stop wall 22, serving to retain said elements against longitudinal displacement. If desired, 50 55

simple forms of tools or fixtures may be used to insert the elements 25, 25a in position.

In Figs. 4 and 5 of the drawing, 17a represents a finger piece or pull of slight modification as to general form and also with respect to the contour of the recess provided in one surface thereof; that is to say, the recess 20a is provided on opposed side walls with notches 21 to receive corresponding projecting lugs 28 on characterized elements 29, 29a of the same general type as the elements 25, 25a. With this construction, the member 24, shown in Fig. 1, is dispensed with and the projecting lugs serve the same purpose; that is to say, prevent longitudinal movement of the elements 29, 29a one with respect to the other.

In forming the devices 17, 17a by die casting processes, it is desirable to simplify the casting operation to cast the pulls with straight side walls as at 30, Fig. 6 of the drawing, forming slightly protruding portions 31 on the surface of the pull adjacent the walls 30. In completely forming the device, pressure is applied to the recessed side surface of the pull to displace the raised material 31 and form the inwardly extending flanges which produces what might be termed a dovetail socket 32 as represented in Fig. 7 of the drawing, the result of which will be the inturned flanges, as for example at 21, in Fig. 2 of the drawing, which retains the characterized elements against lateral displacement.

Another form of construction is shown in Figs. 8, 9 and 10 of the drawing wherein a pull 17b is provided with a recess 20b having substantially straight boundary walls. With this pull, a relatively wide aperture 33 is provided centrally of the recessed portion thereof and two narrow apertures 34 and 35 are provided at the ends of said recess. These apertures register with recesses 33a, 34a and 35a on the under surface of the pull. With this construction, characterized elements 36, 36a are each provided with end walls as may be seen upon a consideration of Fig. 9 of the drawing. These end walls terminate in projecting lugs 37, which extend through the apertures 33, 34 and 35 and are adapted to be folded and compressed onto and arranged within the recesses 33a, 34a, 35a as clearly seen in Fig. 9 in securing the elements 36, 36a in position. With the construction shown in Figs. 8, 9 and 10, as well as in Figs. 11 and 12, a hammer or other tool may be utilized in bending over the projecting lugs or retaining clips 37.

In Figs. 11 and 12 of the drawing, another form 55 of finger piece or pull 17c is illustrated which differs from the structure shown in Figs. 8, 9 and 10, simply in providing two pairs of apertures 38 at opposite sides of the finger piece to receive projecting lugs or clips 37a, similar to the clips 37 60 and which enter recesses 39, registering with the apertures 38 as seen for example in Fig. 12 of the drawing.

It will be understood that generally speaking the complete fastener devices will have the pulls attached thereto with the recesses left blank. The merchant or storekeeper will be provided with a supply of the various characterizing elements and when the fastener is sold or when an article of merchandise having a fastener thereon is sold, the initials of the purchaser may be applied to the pull or any other symbol or characterized elements may be applied to give ornamentation to the device, or in classifying it or characterising it in any way. Regardless of the 75 particular type and kind of pull employed; that is

to say, from a structural standpoint, the elements may be formed of any suitable material and in any desired manner, such as stampings from suitable sheet material or by pressure molding or forming such materials as employed in the slider. 8 On the other hand, these devices may be formed from cellulose acetate. It will thus be seen that any type or kind of color or color combinations may be employed in the elements to give added distinction and characterization thereto. In 10 utilizing such materials as cellulose acetate in the formation of the devices when constructed and used substantially as shown in Figs. 8 to 12 inclusive, means will be provided to soften the lugs, for example by the application of heat or 15 other means of softening the material to permit the shaping or bending thereof.

In using metallic characterized elements, the same may be composed of suitable materials which will produce an attractive appearance 20 apart from any treatment thereto; where on the other hand, the said elements may be plated by any of the known processes to produce any desired finish or effect not only from a standpoint of lustre but from a standpoint of color. 25

The recesses, such for example as the recess 20 in Fig. 1, of the respective pulls may be said to form panels on the pull for the reception of the characterized elements. These panels have means, for example, the inturned flanges, apertures, walls, and projections, for receiving parts or sections of said elements in retaining the elements against displacement from the panels. 30

In the accompanying drawing, all of the pulls are shown of more or less one general shape and 35 form. It will be understood, however, that the contour or design of the pull may be modified to suit the various uses to which the fasteners are applied. In like manner, it will be apparent that two or more characterized elements may be 40 coupled with the pull in any desired arrangement, which will be consistent with the shape and contour of the pull.

Having fully described my invention, what I claim as new and desire to secure by Letters 45 Patent, is:

1. A finger piece for the sliders of separable fasteners adapted for the mounting of characterized elements thereon, said finger piece comprising a relatively long flat die cast body, a pivotal means at one end portion of said body for movably coupling the finger piece with a slider, one side surface of the other end portion of said body having an elongated recess, the side walls of said recess being inclined toward each other providing a substantially dovetail cross-sectional contour to said recess and forming means whereby a plurality of predetermined characterized elements may be retained against lateral movement in said recess, and said body 55 at predetermined points bounding said recess having means retaining the elements arranged in said recess against longitudinal movement therein and against displacement from said finger piece.

2. A finger piece for the sliders of separable fasteners adapted for the mounting of characterized elements thereon, said finger piece comprising a relatively long flat die cast body, a pivotal means at one end portion of said body for movably coupling the finger piece with a slider, one side surface of the other end portion of said body having an elongated recess opening through said end thereof, the side walls of said recess being inclined toward each other providing a 70 75

substantially dovetail cross-sectional contour to said recess and forming means whereby a plurality of predetermined characterized spring elements may be retained against lateral movement in said recess, said body having a closed end wall at one end of said recess and an outwardly projecting lug at the other open end thereof intermediate the side walls of said recess, and said end wall and lug forming means retaining the elements against displacement from said finger piece.

3. A finger piece for the sliders of separable fasteners adapted for the mounting of characterized elements thereon, said finger piece comprising a relatively long flat die cast body, a pivotal means at one end portion of said body for movably coupling the finger piece with a slider, one side surface of the other end portion of said body having an elongated recess opening through said end thereof, the side walls of said recess being inclined toward each other providing a substantially dovetail cross-sectional contour to said recess and forming means whereby a plurality of predetermined characterized spring elements may be retained against lateral movement in said recess, said body at predetermined points bounding said recess having means retaining the elements arranged in said recess against longitudinal movement therein and against displacement from said finger piece, and said last named means comprising pairs of offset portions at spaced intervals along the side walls of said recess adapted to engage corresponding offset portions on the elements arranged therein.

35 4. A finger piece for the sliders of separable fasteners, said finger piece comprising a relatively long flat die cast body, a pivotal means at one end portion of said body for movably coupling the finger piece with a slider, one side surface of the other end portion of said body having an elongated recess, characterized elements arranged in said recess, said body at predetermined points in said recess having spaced apertures passing through said body and registering with small recesses on the opposed side surface of said body, and projecting members

on opposed edges of said elements extending through said apertures and arranged in said small recesses in securing the elements to said finger piece.

5 5. In combination a finger piece for separable fasteners of the class described and a plurality of characterized elements detachably arranged to form a panel on one side surface of said finger piece, said finger piece comprising a relatively long flat body, one end portion of said body having a mounting crosshead, the other end portion of said body having an elongated recess adapted to receive said elements, the side walls of said recess having means engaging the edges of said elements adjacent the same in retaining 10 said elements against lateral displacement from said finger piece, said elements intermediate said last named edges thereof having a transverse cross-sectional contour comprising one continuous uniradiial curve, and other cooperating means 15 on said body and elements for retaining said elements against longitudinal movement in said recess and against accidental displacement from said finger piece.

20 6. In combination a finger piece for separable fasteners of the class described and a plurality of characterized thermoplastic elements detachably arranged to form a panel on one side surface of said finger piece, said finger piece comprising a relatively long flat body, one end portion 25 of said body having a mounting crosshead, the other end portion of said body having an elongated recess adapted to receive said elements, said elements having a surface of cylindrically curved contour extending to the side edges thereof, the side walls of said recess having means engaging the side edges of said elements adjacent the same in retaining said elements against lateral displacement from said finger piece, said body at predetermined points bounding 30 said recess having offset portions forming means retaining said elements against longitudinal movement in said recess and against accidental displacement from said finger piece.
